UNITED STATES PATENT OFFICE

FERDINAND A. BUESCHER, OF ELKHART, INDIANA

KEY MECHANISM FOR WIND MUSICAL INSTRUMENTS

Application filed March 3, 1927. Serial No. 172,378.

This invention relates to improvements in key mechanism for wind musical instruments.

As is well known in the art of saxophone construction it has heretofore been the practice, which has become conventional, for manufacturers of saxophones to have a relatively narrow connecting arm extending from a key in such manner as to contact with a relatively narrow lever, the actuation of which lever makes Bb when the instrument is played. Said connecting arm is invariably provided on its contact edge with a narrow strip of cork. In use the small contact surface between this narrow strip of cork and the relatively narrow lever causes the cork to wear rapidly or become compressed so that the key fails to close fully, causing a leak, and the instrument cannot be played. This necessitates frequent replacement of the cork bearing strip as well as considerable annoyance. My invention is therefore designed primarily to overcome these defects without detracting from the playing qualities of the instrument, but rather to facilitate and improve them.

With the foregoing general object in view my invention contemplates the provision of a means primarily for securely closing the key pad seat to make Bb on a saxophone, thus preventing leakage which results in a false note or absolute failure.

Another object of the invention is to provide a substantial contact surface between the lever or levers which must be actuated to make Bb on a saxophone and the actuating member, whereby the wear of said contact surface will be very slight and such wear as occurs will be compensated by reason of the particular construction of the member provided with such contact surface, so that the key pad will always close tightly on its seat when operated.

Another essential object of the invention resides in providing a self-aligning bearing having an extended active surface disposed lengthwise of the lever to be depressed, and with such means constructed and arranged to provide for the key of Bb to be tightly closed, at all times, when making such note,

thus preventing leakage and insuring satisfactory playing of the instrument by the musician.

Further objects of the invention are to provide, in a manner as hereinafter set forth, a key mechanism for the purpose referred to, which is comparatively simple in its construction and arrangement, strong, durable, compact, thoroughly efficient in its use, readily assembled, and comparatively inexpensive to manufacture.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a fragmentary view in plan of a musical instrument of the wind type illustrating a key mechanism therefor in accordance with this invention.

Figure 2 is a fragmentary view of a wind instrument, in side elevation illustrating a key mechanism therefor in accordance with this invention.

Figure 3 is a section on line 3—3 Figure 1.

Figure 4 is a section on line 4—4 Figure 3.

Figure 5 is a fragmentary view, in cross section, of a modification.

Figure 6 is a fragmentary view, in side elevation of another modification.

Referring to the drawings in detail, 1 indicates a tubular body, which is a fragment of a saxophone, and is provided with lateral openings 2, surrounded by rims 3, which constitute seats for the valves of the keys of the instrument. As illustrated each valve comprises a pad 4, carried by a pad cup 5, and to the latter is fixedly secured a lever or crank arm for shifting a valve to engage a rim to close an opening 2.

The valve of the B flat key is indicated at 7, and its lever at 8, and the latter is carried

by and extends inwardly from a rock shaft 9. Fixed to a shaft 9' is the outer end of a lever arm 10 which is positioned an appropriate distance from the lever 8. The shafts 9, 9' are arranged in spaced relation and 5 revolvably mounted on a stationary supporting bar 11, which is supported from and offset with respect to the body of the instrument. The shafts 9, 9' are connected together by a coupling means 9'' whereby they will shift in unison. Key valves are indicated at 10 12, 13 and each of which has a lever 6 attached to a tubular shaft loosely mounted on a rod 14'. That shaft which is connected to the lever 6 of key valve 12 is indicated at 15 14 and that shaft attached to the lever 6 of key valve 13 at 14''. The valve 12 can be operated independently of valve 13. A means indicated at 12', of known construction is 20 employed for operating the valves 12, 13 synchronously, when the sleeve 14'' is shifted on the rod 14. The means 12' is carried by the opposed ends of shafts 14', 14''. The valve 12 carries a key or finger piece 15 for operating it independently of valve 13.

The valve 13 has fixed thereon, diametrically thereof, a laterally projecting arm 16 of appropriate length and which is provided on its inner edge with a pair of spaced transversely extending grooves 17, 18, positioned a substantial distance from the edge of the valve 13. Eccentrically pivoted in the grooves 17 and 18, are self aligning bearing elements 19, 20 each of a length greater than 30 either of the grooves and which project an appropriate distance from each side face of the arm 16. Each bearing element is of segmental contour and has secured to its flat inner edge a strip 21 of substantial thickness and formed of cushioning material, preferably cork.

The bearing elements are eccentrically connected to the arm 16 by means of a common pivot pin 22 therefor, and the said bearing 45 elements project from the inner edge of said arm 16.

The element 19 is positioned over the lever arm 10, and is adapted to ride thereon for the purpose of depressing it whereby the lever 50 arm will shift the shafts 9, 9' in unison, thus closing the valve 7. The lever arm 10 has its upper or outer edge provided with a lengthwise extending, flat bearing surface 24, inclining downwardly towards the free or inner 55 end of the arm. The said bearing surface 24 is of greater length than the length of the pivoted bearing element 19 which is disposed lengthwise with respect to said surface 24.

The pivoted bearing element 20 coacts with 60 a lever arm 23 for the purpose of depressing it. The lever arm 23 is constructed in the same manner as the lever arm 10. The lever arms 10 and 23 are oppositely disposed with respect to each other. The cushioning strips 65 for the bearing elements, when these latter

are active, ride for their entire length upon the bearing surfaces on said lever arms, whereby any compression applied to the strips will be uniform throughout, under such conditions the strips will wear in a uniform manner.

The lever arm 23 has its outer end fixed to a tubular rock shaft 24', revolvably mounted on the stationary supporting bar 14'. Operated from the shaft 24', is a spring controlled depressible key valve 26, carried on the inner end of a lever arm 27. The arm 27 is fixedly secured at its outer end to the rock shaft 24', and is shifted by the latter when the shaft 24' is rocked. The arm 27 is provided with an extension 27'. The pivoted bearing element 20 and lever arm 23 associate with the valve 26.

Key devices for shifting the shaft 24', independent of the shifting thereof by the lever arm 23, are indicated at 28 and 30. The key device 28 includes an arm 28' which engages the extension 27'. The key device 30 is connected to shaft 24'.

The valve 26 can be depressed simultaneously with valve 7, by depressing valve 12 through the means of the key 15. On the depressing of valve 12, valve 13 will simultaneously move to closed position, and the pivoted bearing elements 19, 20, riding against the bearing surfaces 24, will depress the lever arms 10 and 23 thereby closing valves 26 and 7. The valve 7 is provided with a key 31, so it can be closed independently of valve 13.

In the modified form illustrated in Figure 5, the laterally extending arm or bracket 32, is provided with but a single self-aligning pivoted bearing element 33, pivoted at 34 and which coacts with the lever arm 10 for the purpose of depressing the valve 7 to make Bb. The single pivoted bearing element 33 is mounted in the same manner as the double bearing elements illustrated in Figures 1 and 2.

In the modified form shown in Figure 6, the valve 26 is operated from the free end of the arm 35, which has mounted therein and depending therefrom a self-aligning pivoted bearing 36, constructed in the same manner as the bearing elements 19, 20 and 33. The bearing 36 associates with the lever arm 10' to depress it. The arm 35 is carried by and extends laterally from the valve 13 and is of a length to overlie the valve 26. That part of the arm 35 which overlies the valve 26, is provided with a cork strip or other suitable cushioning material as indicated at 37. The construction provides for the depressing or rather closing of the valve 26 when valve 13 is depressed to closed position and provides for the actuation of valve 7 to make Bb.

In my invention the arms 16, 32 or 35 do not engage with the lever arms directly, but instead each lever arm is engaged by a self-

aligning pivoted bearing element disposed lengthwise of such lever arm and which provides means to always insure a tight seating of the valve of Bb or other valve or valves to prevent leakage. The lever arms 5 10 and 23 are relatively movable with respect to the valve 13.

As to the operation of the mechanism for the making of the key of Bb, in certain passages, it is more convenient to make the key 10 with the first finger of the right hand, although it can be accomplished by using the side key. This is done by using the inside knuckle of the right hand and the first two 15 fingers of the left hand. B flat can also be made with the first finger of the left hand and at the same time press the button between the first finger button and the second finger button of the left hand.

20 It should be understood that the spirit of my invention is really the interposing of a self-aligning pivoted bearing element between an arm extending from a valve and a lever arm for actuating another valve or 25 valves whereby a sliding contact along a substantial bearing surface will be afforded, as between the arm on the valve and the lever arm. That therefore it makes no material difference, so far as the spirit of my 30 invention is concerned whether said pivoted bearing element is pivoted to the valve arm in the path of the lever arm, or pivoted to the lever arm in the path of the valve arm.

It is thought that the many advantages 35 of a key mechanism for the purpose set forth, constructed in the manner aforesaid, can be readily understood, and although the preferred embodiments of the invention are as illustrated and described, yet it is to be understood that changes in the details of construction may be made without departing 40 from the spirit of the invention as claimed.

What I claim is:

1. A key mechanism for wind musical instruments comprising a valve, an arm radially projecting from one side of said valve, a member eccentrically pivoted to and disposed transversely of said arm, said member provided with a flat face to provide a substantial bearing surface to traverse a cooperating lever arm.

2. In a device of the character described, relatively movable members, self-adjusting means on one member and in the path of 55 movement of the other member for simultaneous movement of both members, when one member is actuated.

3. In a key mechanism for musical instruments, a bodily depressible suspension means 60 provided on its inner side with a pivoted bearing element adapted, when said means is depressed, to traverse and actuate a key valve depressing device for tightly closing the key valve associated with said device.

65 4. In a key mechanism for musical instru-

ments, a depressible key valve provided with laterally extending suspension means bodily carried therewith, a pivoted bearing element supported by and extending from the inner side of said means and adapted when said means is depressed by said key valve to traverse and actuate a key valve depressing device for tightly closing the key associated with said device. 70

5. In a valve mechanism for musical instruments, a depressible key valve provided with means bodily carried therewith for tightly closing a pair of valves when said depressible valve is moved to closed position, said means including a projecting suspended, 75 pivoted, self-aligning bearing element. 80

6. In a key mechanism for musical instruments, a key valve depressing device having as a part thereof a lever arm, a bodily depressible suspension means provided with a projecting pivoted bearing element traversing said arm when said means is depressed to actuate said device for tightly closing the key valve associated therewith. 85

7. In a key mechanism for musical instruments, a key valve depressing device having as a part thereof a lever arm, a bodily depressible suspension means provided with a projecting pivoted bearing element traversing said arm when said means is depressed to actuate said device for tightly closing the key valve associated therewith, said lever arm having an inclined surface traversed by said element. 90

8. In a key mechanism for musical instruments, a key valve depressing device having as a part thereof a lever arm, a bodily depressible suspension means provided with a projecting pivoted bearing element traversing said arm when said means is depressed to actuate said device for tightly closing the key valve associated therewith, said lever having an inclined surface traversed by said element, said element disposed lengthwise with respect to said arm. 100

9. In a key mechanism for musical instruments, a key valve depressing device having as a part thereof a lever arm, a bodily depressible suspension means provided with a projecting, pivoted, adjustable bearing element traversing said arm when said means is depressed to actuate said device for tightly closing the key valve associated therewith, said lever arm having an inclined surface traversed by said element, and said element disposed lengthwise with respect to said surface. 115

10. In a key mechanism for wind musical instruments, a key valve depressing device having as a part thereof a lever arm, and a bodily depressible means arranged over said arm and including an automatically adjustable bearing element projecting therefrom for lengthwise traversing said arm when said means is depressed to actuate said device for 125

tightly closing the key valve depressed thereby.

11. In a key mechanism for wind musical instruments, a key valve depressing device having as a part thereof a lever arm, a depressible key valve having a laterally extending arm, and an automatically adjustable bearing element carried by and extending transversely of said lateral arm and further interposed between said arms whereby the depressing of said key valve will depress the lever arm to actuate said device for tightly closing the key valve depressed thereby.

12. A key mechanism for wind musical instruments, comprising a key valve, an arm carried by said key valve, a lever underlying said arm, a pivoted self-adjusting member interposed between said arm and said lever for shifting the latter, said member being carried by and disposed transversely of said arm and extending lengthwise of said lever.

13. A key mechanism for wind musical instruments comprising an arm carried by a depressible valve, a lever underlying said arm and having a flat bearing surface, and a pivoted self-adjusting bearing member having a flat face for traversing said surface when the valve is depressed to depress said lever, said member disposed transversely with respect to and carried by said arm.

14. A key mechanism for wind musical instruments comprising an arm carried by a depressible valve, a lever underlying said arm and having a flat bearing surface, and a pivoted self-adjusting bearing member having a flat face for traversing said surface when the valve is depressed to depress said lever, said member disposed transversely with respect to and carried by said arm, said member extending laterally in both directions with respect to said arm and lengthwise with respect to said lever.

15. A key mechanism for wind musical instruments comprising an arm carried by a depressible valve, a lever underlying said arm and having a flat bearing surface, a pivoted self-adjusting bearing member having a flat face for traversing said surface when the valve is depressed to depress said lever, said member disposed transversely with respect to and carried by said arm, said member extending laterally in both directions with respect to said arm and lengthwise with respect to said lever, and said member being eccentrically pivoted.

16. A key mechanism for wind musical instruments comprising an arm carried by a depressible valve, a lever underlying said arm and having a flat bearing surface, a pivoted self-adjusting bearing member having a flat face for traversing said surface when the valve is depressed to depress said lever, said member disposed transversely with respect to and carried by said arm, said member extending laterally in both directions

with respect to said arm and lengthwise with respect to said lever, and said bearing surface inclining downwardly toward one end of the lever.

In testimony whereof, I affix my signature 70
hereto.
